DESIGN FOR A SHOE TREE

I. Lawrence Lesavoy, Allentown, Pa.

Application November 10, 1945, Serial No. 123,650

Term of patent 14 years

(Cl. D7—3)

To all whom it may concern:

Be it known that I, I. Lawrence Lesavoy, a citizen of the United States, resident of Allentown, in the county of Lehigh, State of Pennsylvania, have invented a new, original, and ornamental Design for a Shoe Tree, of which the following is a specification, reference being had to the accompanying drawing, forming part thereof.

In the drawing,

Figure 1 is a top plan view of the shoe tree showing my new design.

Figure 2 is a side view thereof, and
Figure 3 is a bottom view thereof.

I claim:

The ornamental design for a shoe tree, substantially as shown.

I. LAWRENCE LESAVOY.
